UNITED STATES PATENT OFFICE.

CHARLES S. FINNEY, OF CHICAGO, ILLINOIS.

DESIGN FOR A BEARD-SOFTENER.

57,628.

Specification for Design. Patented Apr. 26, 1921.

Application filed August 1, 1919. Serial No. 314,768. Term of patent 3½ years.

To all whom it may concern:

Be it known that I, CHARLES S. FINNEY, a citizen of the United States, residing at Chicago, in the county of Cook and State of Illinois, have invented a new, original, and ornamental Design for a Beard-Softener, of which the following is a specification, reference being had to the accompanying drawing, forming part thereof.

Fig. 2 is a central vertical sectional view thereof.

I claim:—

The ornamental design for a beard softener, as shown.

CHARLES S. FINNEY.
